UNITED STATES PATENT OFFICE.

WILLIAM H. MINER, OF CHICAGO, ILLINOIS.

BACKING-STRIP FOR REFRIGERATOR-CAR-DOOR PACKING.

992,793.

Specification of Letters Patent. Patented May 23, 1911.

Application filed March 10, 1911. Serial No. 613,541.

To all whom it may concern:—

Be it known that I, WILLIAM H. MINER, a citizen of the United States, residing in Chicago, in the county of Cook and State 5 of Illinois, have invented a new and useful Improvement in Backing-Strips for Refrigerator-Car-Door Packing, of which the following is a specification.

My invention relates to improvements in 10 packing backing strips for refrigerator car doors.

My invention consists in a packing backing strip formed of a strip of sheet metal 15 bent into loop form in cross section, with flat inner and outer faces and curved end walls, and having coiled springs secured thereto at intervals by staples which are inserted through holes formed at the meeting edges of the backing strip, and which thus connect 20 the meeting edges of the backing strip as well as secure the coiled springs thereto.

In the accompanying drawing forming a part of this specification, Figure 1 is a horizontal, sectional perspective view of a device 25 embodying my invention. Fig. 2 is a detail, horizontal section. Fig. 3 is a detail rear elevation of the backing strip. Fig. 4 is an end view looking from the line 4—4 of Fig. 3. Fig. 5 is a detail end view of one 30 of the coiled springs. Fig. 6 is a detail elevation of the spring. Fig. 7 is a detail view of the staple.

In the drawing, 1 represents a portion of the frame of a refrigerator car door having 35 a longitudinal channel 2 to receive the backing strip for the packing, and circular recesses 3 to receive the coiled springs of the packing strip at intervals throughout its length.

40 4 is the yielding packing secured to the member 1 and extending across the channel or recess 2 therein and secured thereto by wire brads or nails 5 in connection with the flexible facing strip 6. The yielding packing 4 and its facing strip 6 are pressed yielding- 45 outward and backed up in order to produce a tight joint at the edge face of the door with the door jamb or door frame by means of a sheet metal backing strip 7 50 curved into loop form in cross section, and having a flat outer face 8, a flat inner face 9 and curved end walls 10, 10, and which fits in the channel 2 of the door member, and

which is provided at intervals throughout its length with coiled springs 11 which are 55 secured to the backing strip 7 by staples 12, which pass through holes 13 formed in the loop shaped backing strip 7 at the meeting edges 14 thereof, and which staples embrace the diametrically extending end 15 60 of the coiled spring. The prongs of the staple, after being inserted through the holes at the meeting edges of the backing strip are bent or clenched down as shown at 65 16, thus firmly uniting the same to the backing strip and forming a loop on the inner face of the backing strip, through which the securing end 15 of the spring 11 may be inserted. The curved edge walls 10 of the backing strip prevent the packing 4 and 70 its facing strip 6 from forming any abrupt outwardly projecting shoulder to interfere with the proper shutting of the door and the compression of the packing by the closing of the door. The coiled springs 11 bear 75 at their inner ends against the ends of the circular recesses 3 and at their outer ends against the inner flat face of the backing strip.

I claim:—

1. In a door packing, the combination of 80 a member furnished with a packing channel, of a packing and flexible facing strip bridging said channel, and a sheet metal backing strip curved into loop form in cross section, and having flat outer and inner faces and curved edges uniting its flat inner and outer faces, coiled springs and staples securing the ends of said coiled springs to the edges of said sheet metal backing strip, substantially as specified. 85

2. A packing backing strip for refrigerator car doors, consisting of a strip of sheet metal bent into loop form in cross section, with flat inner and outer faces, and provided at intervals with coiled springs secured thereto by staples, substantially as specified. 95

3. A packing backing strip for refrigerator car doors, consisting of a strip of sheet metal bent into loop form in cross section, with flat inner and outer faces, and provided at intervals with coiled springs secured thereto by staples, the meeting edges of said loop shaped backing strip being furnished with holes for the staples to pass through, 100 and the springs being provided with dia- 105

metrically extending securing ends inserted through the staples, substantially as specified.

4. A backing strip for door packing, consisting in a sheet metal strip bent into loop shape in cross section, provided with holes at its meeting edges, and furnished with a coiled spring secured thereto, and a staple

passing through said holes in the meeting edges of the strip and embracing the end 10 of the coiled spring, substantially as specified.

WILLIAM H. MINER.
